UNITED STATES PATENT OFFICE.

SINGLETON BERRY BEDINGER, OF TERRELL, TEXAS.

COMBINED TROUSERS-STRETCHER AND COAT-HANGER.

No. 830,874.

Specification of Letters Patent.

Patented Sept. 11, 1906.

Application filed September 29, 1905. Serial No. 280,630.

To all whom it may concern.

Be it known that I, SINGLETON BERRY BEDINGER, a citizen of the United States, and a resident of Terrell, in the county of Kaufman and State of Texas, have invented a new and Improved Combined Trousers-Stretcher and Coat-Hanger, of which the following is a full, clear, and exact description.

The object of the invention is to provide an extremely simple, novel trousers-stretcher formed of resilient wire rods, and a coat-hanger of similar material, these co-operative devices being so combined that the coat-hanger adds to the efficiency of the trousers-stretcher when both are employed together, a further object being to so construct the trousers-stretcher and coat-hanger that they may be used separately and be equally effective if this is desired.

20 The invention consists in the novel construction and combination of parts, as is hereinafter described, and defined in the subjoined claims.

Reference is to be had to the accompanying drawings, forming a part of this specification, in which similar characters of reference indicate corresponding parts in all the figures.

Figure 1 is a side view of the trousers-stretcher appliance engaged within the legs of a pair of trousers shown by dotted lines and the coat-hanger device engaged with limbs of the trousers-stretcher and aiding their divergence. Fig. 2 is a detached perspective view of the trousers-stretcher and of the coat-hanger, combined together for co-operative service; and Fig. 3 is a detached side view of one-half section of the trousers-stretcher.

40 The trousers-stretcher comprises two similar half-sections A, each section in use being inserted into a respective leg of a pair of trousers for their distension flatwise. As shown, each section of the two-part stretcher device is formed of a single wire rod of sufficient length, bent into form as follows: At the longitudinal center of the wire rod a coil a is formed, and on each equal portion b thereof, which extends outwardly and downwardly from said coils an equal distance, a substantially U-shaped bend c is formed, thus disposing the two equal remaining portions d of the resilient material parallel with each other, as is clearly shown in Fig. 3, and it will be obvious that the coil a adapts these limbs d to spring flat after being compressed

toward each other. On the ends of the limbs d on each stretcher-section A a hook e is formed, which hooks are preferably bent inward and downward in the same plane with the coil a and-spreader-limbs d.

The coat or vest hanger B is formed of a resilient wire rod, having a single coil g formed at its center of length, from which project oppositely two body members h, and at an equal distance from said coil an eye i is formed on each body member and from each eye the remaining portions m of the wire-rod material project oppositely in the same plane with the body member h, and preferably are equally arched, thus adapting them to conform to the shape of the shoulders of a coat or vest that may be hung for support on the hanger device.

In the combined use of the two stretcher sections or frames A with the hanger B the frames A are each passed from the body portion of a pair of trousers down into a respective leg C and are disposed therein so that the limbs d will respectively engage the front and rear portions of the trousers-leg at their transverse centers, as is indicated for one leg in Fig. 1. The insertion of each section or frame A into a trousers-leg will compress the limbs d thereof toward each other, so that considerable outward pressure will result and the limbs will produce creases in the legs of the trousers at their front and rear sides, the coils a enforcing this pressure of the limbs. The coat-hanger B is now connected with the hooks e on the ends of the limbs d by the insertion of the free-ends of the hooks down into the eyes i, and the width between said eyes may be such that the body members h whereon the eyes are formed, require compression toward each other to permit the hooks e to pass down into the eyes, this compression serving to increase the tension of the spring-coil g. Upon relaxing pressure thereon the body members h will resume normal adjustment, and this will increase the distending strain had by the limbs d, due to the tension of the spring-coil g tending to spread apart the eyes i. The coat-hanger B may now be utilized for the support of a vest or coat engaged therewith in an obvious manner, and the trousers and coat or vest may be hung upon a hook or other stable projection from a wall by an engagement with the coil g.

The trousers may be placed in creased condition by placing the stretcher-frames A

in the legs of the garment when packed into a suit-case or trunk, so that by the use of the improved stretcher device the garment will always be kept from becoming wrinkled or 5 baggy at the knees.

Having thus described my invention, I claim as new and desire to secure by Letters Patent—

1. A trousers-stretcher comprising two frames of resilient wire each having a pair of limbs, a spring-coil adapted for diverging the free ends of each pair of limbs, said free ends being provided with hooks, and a hanger having eyes for engaging the hooks, said hanger 15 serving to support the stretchers and to maintain the limbs substantially parallel.

2. A trousers-stretcher comprising two frames each formed of a wire rod having a spring-coil formed at the center of the wire 20 material, two members extended oppositely from the coil, two U-shaped bends at the respective ends of said members, two limbs projected from the U-shaped bends, hooks bent on the ends of the limbs, and a rod having 25 eyes for engaging the hooks, and a central loop whereby to suspend the stretchers.

3. The combination with a stretcher-frame comprising two resilient limbs spaced apart by a spring-coil, and two straight frame 30 members extended oppositely from the coil, and a hook on the free end of each limb, of a

garment-hanger comprising two body members of wire-rod material spaced apart by an integral spring-coil, eyes at an equal distance from the spring-coil, and body members extended from the eyes, said eyes receiving the hooks on the ends of the pair of limbs when said limbs are compressed by their insertion within the leg of a garment.

4. The combination with a pair of stretcher-frames, each comprising a spring-coil, two members extended outward and downward from said coil, U-shaped bends at the ends of said members, resilient limbs extended from the U-shaped bends, and hooks formed on the free ends of the limbs, of a hanger device embodying a central spring-coil, body members of wire extended oppositely from the spring-coil, eyes formed on these body members, and extensions of the body members projected from the eyes, said extensions being similarly arched, the hooks on the trousers-stretcher limbs engaging the eyes, said limbs being distended by the tension of the coil on the hanger device.

In testimony whereof I have signed my name to this specification in the presence of two subscribing witnesses.

SINGLETON BERRY BEDINGER.
